UNITED STATES PATENT OFFICE.

ZACHARIAH ADAM HALL, OF HESPELER, ONTARIO, CANADA.

HOCKEY STICK.

Application filed November 26, 1924. Serial No. 752,445.

The object of my invention is to devise a strong, durable and uniformly finished hockey stick that can be inexpensively manufactured and for the construction of which, 5 wood can be used that heretofore has been considered factory scrap or waste.

This object is attained by separately making the handle and blade, and so jointing them that when the parts are properly assembled the tensile strength and durability 10 of the stick will be at least equal to, if not greater than, the tensile strength and durability of a hockey stick in which the blade is integral with the handle.

15 In the production of a hockey stick from a single piece of wood there is necessarily a considerable amount of waste in the shaping of the handle and blade, and the loss or waste of material in the manufacture is approximately equal to the amount in the manufactured product. By separately making the blade and handle parts there is 20 practically no waste of material in the shaping of the handle and very little waste of material in the making of the blade, and it is possible to obtain, according to this invention, approximately double the amount 25 of production that can be obtained from the same quantity of raw material when the 30 blade and handle are of an integral nature. By separately making the hockey stick parts it is possible to use for the blade a strong, tenacious material having more or less resiliency or spring and to use a rigid material 35 for the construction of the handle, thereby obtaining the advantage of the full driving force of the stick without risk of breakage under reasonable conditions of use.

For an understanding of the invention 40 reference is to be had to the accompanying drawing in which,

Fig. 1 is a fragmentary side elevation partly in section of a hockey stick, and

45 Figs. 2 and 3 are similar views to Fig. 1 showing modified forms of construction.

Like numerals of reference refer to like parts throughout the specification and drawing.

The hockey stick consists of two separately constructed parts viz:—a handle 1 and blade 2, with the grain of the wood running lengthwise of each part. By separately making the blade and handle, it is possible to use wood of any kind, weight, or texture 55 in the blade and to use a different wood in the handle of the same stick, so that the de-

sired strength and balance required by 60 hockey players may be acquired. In the constructions shown in Figs. 1, 2 and 3, the handle part, from a point interjacent its ends, is tapered to form an elongated tongue 5 of substantially V-shape.

In Fig. 1 the tongue 5 is shown to be made by gradually tapering the handle part from a point interjacent its ends to approximately the throat 10 of the blade. 65

In Fig. 2 the forward edge of the handle part has a substantially V-shaped notch 3 and from the notch 3 and a corresponding point on the opposite edge, the handle part 70 tapers to form the tongue 5.

As shown in Fig. 3 the forward edge of the handle part 1 has a substantially V-shaped notch 3 and the opposite edge has a recess 4 in line with the notch 3. From the 75 notch 3 and recess 4 the handle is tapered to form the tongue 5.

Integral with the blade 2 is an arm 6 that is angular to the blade. The arm 6 is formed with a recess 8 extending inwardly from the free end of the arm and of corresponding location, shape and dimensions to the tongue 5, this recess providing the arm with two forks, 9, 9^a. 80

In Fig. 1 the ends of the forks 9, 9^a are 85 tapered to match both edges of the handle part.

In Fig. 2 the end of the fork 9 is entered in the notch 3 and the end of the fork 9^a is tapered until it matches with the corresponding edge of the handle. 90

In Fig. 3 the end of the fork 9 is entered in the notch 3 and the end of the fork 9^a is entered in the recess 4. 95

The tongue 5 and the walls of the recess 8 are accurately jointed together and the joint is secured by nails, wood-screws, or other suitable means 7 inserted through the arm. 100

The recess 8 and tongue 5 extend to a point opposite the throat 10 of the blade. In hockey sticks where the blade and handle parts are integral the throat is the weakest part of the stick and the point where the stick has the greatest tendency to break or bend. By separately constructing the blade and handle parts and extending the tongue 5 to a point opposite the throat 10 the stick is strengthened at the throat to resist, under reasonable conditions of use, 110 the bending and breaking strains to which the stick is subjected.

Having thus fully described my invention what I claim as new and desire to secure by Letters Patent is:

1. A hockey stick comprising a handle part one edge of which has a V-shaped notch interjacent its ends, said handle part being tapered from the notch and a corresponding point on the opposite edge to form an elongated tongue, and a blade part having an integral arm angular to the blade formed with an elongated recess corresponding in location, shape and dimensions to the tongue of the handle part, said tongue entered in the elongated recess and extending to the throat of the blade, and one of the forks of the arm formed by said recess entered in the notched edge of the handle part.
2. A hockey stick comprising a handle part and a blade part, the said handle part having a V-shaped notch on one side and a recess on the other side interjacent its ends, and tapered from said notch and recess to form a tongue, and said blade part having formed integral therewith an arm angular

to the blade, said arm having an inwardly extending recess corresponding in location, shape and dimensions to the tongue of the handle, to form two forks the end of one of which is entered in said notch and the end of the other of which is entered in the recess, and means for securing the blade part and handle part together.

3. A hockey stick having a handle part and a blade part, said handle part having on one edge interjacent its ends a V-shaped notch, and on the other edge a recess, the handle from said notch and recess being tapered to form a substantially V-shaped tongue, the blade having formed integral therewith an arm angular to the blade, and recessed to receive said tongue, the free ends of the arm adapted for engagement with the said notch and recess, and means for securing the blade part and handle part together.

Dated at the city of Toronto, in the county of York and Province of Ontario, this 4th day of November, A. D. 1924.

ZACHARIAH ADAM HALL.
